(57) **CLAIM**

The ornamental design for a dehumidifier, as shown and described.

DESCRIPTION

FIG. 1 is a front perspective view of a dehumidifier in accordance with the present disclosure;

FIG. 2 is a rear perspective view of the dehumidifier shown in FIG. 1;

FIG. 3 is a view of the dehumidifier shown in FIG. 1 from the front;

FIG. 4 is a view of the dehumidifier shown in FIG. 1 from the rear;

FIG. 5 is a view of the dehumidifier shown in FIG. 1 from the left;

FIG. 6 is a view of the dehumidifier shown in FIG. 1 from the right;

FIG. 7 is a view of the dehumidifier shown in FIG. 1 from the top;

FIG. 8 is a view of the dehumidifier shown in FIG. 1 from the bottom;

FIG. 9 is a front perspective view of a dehumidifier in accordance with the present disclosure;

FIG. 10 is a rear perspective view of the dehumidifier shown in FIG. 9;

FIG. 11 is a view of the dehumidifier shown in FIG. 9 from the front;

FIG. 12 is a view of the dehumidifier shown in FIG. 9 from the rear;

FIG. 13 is a view of the dehumidifier shown in FIG. 9 from the left;

FIG. 14 is a view of the dehumidifier shown in FIG. 9 from the right;

FIG. 15 is a view of the dehumidifier shown in FIG. 9 from the top; and,

FIG. 16 is a view of the dehumidifier shown in FIG. 9 from the bottom.

(Continued)

The broken lines in the figures show portions of the dehumidifier that form no part of the claimed design.
